UNITED STATES PATENT OFFICE

125,997

DESIGN FOR A DRESS

Evelyn Gold, New York, N. Y.

Application January 9, 1941, Serial No. 97,937

Term of patent 3½ years

To all whom it may concern:

Be it known that I, Evelyn Gold, a citizen of the United States, residing in New York city, in the county of Bronx and State of New York, have invented a new, original, and ornamental Design for Dresses, of which the following is a specification, reference being had to the accompanying drawing, forming part thereof, in which—

I claim:

The ornamental design for a dress, as shown.

EVELYN GOLD.
